UNITED STATES PATENT OFFICE.

THOMAS IRVING POTTER, OF EAST ORANGE, NEW JERSEY, ASSIGNOR TO FEDERATED ENGINEERS DEVELOPMENT CORPORATION, OF JERSEY CITY, NEW JERSEY, A CORPORATION OF DELAWARE.

MINIATURE BASEBALL GAME.

Application filed June 21, 1921. Serial No. 479,359.

To all whom it may concern:

Be it known that I, THOMAS IRVING POTTER, a citizen of the United States, residing at East Orange, in the county of Essex and State of New Jersey, have invented certain new and useful Improvements in Miniature Baseball Games; and I do hereby declare the following to be a full, clear, and exact description of the same, reference being had to the accompanying drawings, forming part of this specification.

This invention relates to games or toys and more particularly to a miniature baseball game for indoor use, one object being to provide a game of this character that will contain the essential features of the game as it is played on a regulation playing field.

The playing field of the present device is, of course, of greatly reduced area but it is divided into an outfield and an infield, miniature players being disposed around the field in the various positions usually occupied by players. The bases or bags are denoted in the infield and mechanism is provided for advancing miniature players, representing runners, around the bases at limited and controllable speed by manual operation. Mechanism is provided for pitching and catching the ball, the pitching mechanism being under the control of one of the persons participating in the game. Appliances are also provided for manually batting and fielding the ball, the fielding appliance being such that the speed, with which another participant of the game can field a batted ball, is limited, thus requiring skill for stopping a batted ball and fielding it to a base before the arrival of a runner sought to be advanced to the base by the participant's opponent.

In the accompanying drawings:

Figure 1 is a perspective view of a device embodying the present invention;

Fig. 2 is a top plan view;

Fig. 3 is a vertical cross section on line 3—3, Fig. 2, of the base forming the playing field;

Fig. 4 is a cross section on the line 4—4 of Fig. 2, showing the back stop and net;

Fig. 5 is a side view, in section, of Fig. 4;

Fig. 6 is an elevation, in section, on the line 6—6 of Fig. 2, showing the pitching mechanism;

Fig. 7 is a side elevation, in section, of Fig. 6;

Fig. 8 is a detail view showing a portion of the mechanism for advancing miniature players around the bases;

Fig. 9 is a view of the bat for batting the ball;

Fig. 10 is a view of the fielding bat for fielding a batted ball; and

Fig. 11 is a modified form of fielding bat.

The playing field 1 is formed of the upper plane surface of a base board of any convenient size but preferably of substantially rectangular shape and the playing field is bounded on each side by a retaining fence or wall 2 for preventing the ball leaving the playing field. The playing field is divided into the outfield and infield, as usual, and erected behind one corner of the infield is a backstop 3 having an opening 4 therein through which the ball may pass, a small net 5 being secured around the back of opening 4 for retaining the ball after passing through the opening. Backstop 3 is hingedly secured to the base-board 1 and is supported against the retaining wall 2 but when the apparatus is to be packed the backstop may be folded down so as to lie below the retaining wall as shown in dotted lines in Fig. 5.

On the side of the playing field opposite backstop 3, there is provided a pitching mechanism for delivering the ball toward the backstop. The pitching mechanism consists of a swinging arm 6 loosely mounted on a pivot pin 7 secured in a frame extension 8 on the playing field. As shown in Fig. 7 a stop bar 9 extending inwardly from the wall 2, limits the forward movement of arm 6 and said arm can be pulled backward against the tension of a spring 10 attached to its lower end, the wall 2 limiting this rearward movement. The ball 13 is retained on arm 6 by supporting pins 12 and, in operation, a small handle 11 on the rear of arm 6 is grasped between the fingers of the participant and pulled backward any desired distance and then released. Supporting members 12 will retain the ball until the movement of arm 6 is arrested by stop 9, after which the ball continues on its course toward the backstop 3. For convenience in packing the device the stop 9 is hinged at 9' to the wall 2 and may be

swung upward and the arm 6 folded down below wall 2 as shown in dotted lines in Fig. 7.

As is usual, suitable base indicating means are positioned around the infield and as the present invention contemplates the provision of mechanism for advancing miniature players around the bases, these base indicating means preferably take the form of rollers 15, 16 journaled in any suitable manner in the base board 1, the four rollers being positioned in rectangular formation with roller 16 representing the home base and rollers 15 representing first, second and third base. The preferred form of mechanism for advancing the runners around the bases consists of an endless belt 17 positioned on the rollers 15, 16, a groove or channel 14 being formed in the base board intermediate the several rollers so that the belt will lie below the surface of said board, the rollers also being located below said surface to prevent interference with a ball batted into the field. Miniature figures 19, representing players, are provided with a circular base having a hole therein whereby they may be placed over one of a series of pins 18 secured at proper intervals to the belt 17. Roller 16 is formed with a stem which extends down below the base board and terminates in a detachable handle 20 and by rotating handle 20 and roller 16 belt 17 is caused to travel around the bases or rollers 15, 16 carrying with it the pins 18 and any players that might be mounted thereon.

Other miniature figures 21 are disposed around the entire playing field 1 in the several positions usually occupied by players on a ball field. The apparatus is provided with a bat 22 with which one of the participants of the game must bat the ball as it is delivered by his opponent with the pitching mechanism before described. Pitches not offered at by the batsman are balls or strikes, those passing through the opening 4 in the backstop 3 being strikes and those not passing through said opening being balls. A ball knocked into fair territory on the field is fielded by the batsman's opponent with the use of a fielding bat 24 having an integral enlarged end 23 such as shown in Fig. 10, or if desired the fielding bat may take the form of that shown in Fig. 11 wherein the handle of the bat and the end portion 23 are made separately but connected together by a flexible tube 25 or any other yielding connection.

After the batsman has batted the ball he advances a runner from the home base around the bases as far as he can before his opponent fields the ball back to the infield, and the opponent, on the other hand, seeks to return the ball to one of the bases before the arrival of the runner in order to

make an "out." To facilitate making the "out" at a base, an umpire pin 26 is located at each base for retaining the ball, when placed on the base, against the runner endeavoring to make the base. To retard the fielding of the ball suitable obstructions in the form of strips 27 may be placed around the playing field and the fielder must not pass the ball over these strips. The batsman is likewise handicapped in advancing his runners by making the handle 20 comparatively small, thus limiting the speed of travel of belt 17 and maintaining the proper relation between the opposing participants.

In operation the apparatus is placed on a table or other suitable support, one participant who is to pitch and field stands behind the pitching arm 6 and his opponent who is to bat stands by the backstop 3 with the bat 22 extending in front of same. The ball may be pitched high or low according to the distance arm 6 is pulled back and the batter endeavors to hit it, a strike being called if he misses and the ball passes through opening 4 and a ball being called if it does not pass through said opening. If he succeeds in hitting the ball into fair territory he immediately drops the bat and operates handle 20 thereby carrying one of the figures 19, representing his runner, from the home base toward first base. His opponent, the pitcher, by manipulation with the fielding bat 23 endeavors to shift the ball 13 from the field to the base the runner is seeking to make if he succeeds in placing the ball on that base in such position against the umpire pin that it cannot be pushed away with the runner, the runner is out and is removed from the field. If a batted ball knocks over the miniature figure representing the pitcher or any of the other field players 21 the ball is counted as caught and the batter out.

The ball 13 is made with a chamois cover or other soft material, small shot being incorporated in it to make it non-resilient or dead and the bat 22 being comparatively small, the ball is better prevented from leaving the playing field. Handle 20 for advancing the runners being small, and too rapid shifting of the batted ball being prevented by the strips 27, a considerable degree of skill is required in playing the game, thus adding interest thereto. The provision for variation in the pitching of the ball and consequent difficulty in successfully batting the ball likewise adds to the skill required and the interest of the game.

What I claim is:

1. In a game board of the character described, the combination of a playing field, base indicators arranged in rectangular formation and denoting the infield, means for moving miniature players around the bases, mechanism for delivering the ball to the

batter, means for batting the delivered ball, manually operable means for fielding a ball batted into the field and moving the ball toward a base, and means at each of the 5 bases for assisting in blocking an advancing runner at said bases with the fielded ball.

2. In a game board of the character described, the combination of a playing field, bases indicated on the field, manually operated means for moving miniature players around the bases, means for fielding a batted ball, and means at each base adapted to cooperate with the fielded ball in blocking an advancing base runner.

3. In a game board of the character described, the combination of a playing field, said field being divided into an infield and an outfield, bases indicated on the infield, manually operable means for moving miniature players around the bases, means for fielding a batted ball to a base, means at each base for assisting in blocking an advancing player with the fielded ball, and obstructions positioned in the outfield and 20 the infield for retarding the fielding of the ball to a base.

4. In a game board such as described, a playing field having bases denoted thereon, means for moving miniature players around 30 the bases, means for delivering balls toward the home base, a bat adapted to be manipulated by a participant of the game for batting a delivered ball and a fielding bat adapted to be manipulated by said participant's opponent for fielding a batted ball to a base.

5. In a baseball game apparatus, the combination with a playing field, a ball, and player tokens, of means for pitching a ball 40 and means for fielding a batted ball to a base both under manual control of one operator, means for batting a ball into the field and means for actuating the base runner tokens both under manual control of another operator.

6. In a baseball game apparatus, the com-

bination with a playing field having base indications thereon, miniature players representing a team at bat, means under control of one operator for batting a pitched ball, 50 means under control of said operator for advancing said players around the bases in simulation of base runners, a second set of miniature players supported on said field representing a team in the field and adapted to be knocked over by a batted ball, and pitching means and fielding means each under control of a second operator, said fielding means comprising a bat with which a batted ball may be pushed about the field. 60

7. In a baseball game apparatus, the combination of a playing field having base indications thereon, a set of miniature players representing a team in the field, a second set of players representing a team at bat, 65 means under control of one operator for batting a pitched ball, means under control of said operator for advancing players of the second set around the bases, means under control of a second operator for pitching a 70 ball, manually operated means under control of the second operator for fielding a batted ball, and pins adjacent each of the base indications against which a fielded ball may be positioned to block an advancing base runner.

8. In a baseball game apparatus, the combination with a playing field, a ball, and player tokens, of means for pitching a ball, 80 means for batting a pitched ball into the field, means for actuating the player tokens, and a manually operable fielding stick for moving a batted ball across the field.

9. In a baseball game apparatus, the combination with a playing field, a ball, and player tokens, of mechanical means for 85 pitching a ball, mechanical means for actuating base runner tokens, means for batting a pitched ball, and means for fielding a batted ball to a base, said batting and fielding 90 means both being manually operated.

THOMAS IRVING POTTER.
